Application May 22, 1930, Serial No. 454,547

7 Claims. (Cl. 146—153)

This invention relates generally to slicing machines and, more particularly, to a certain new and useful improvement in machines adapted especially, though not exclusively, for the slicing 5 of bread.

One of the objects of our invention is to provide for the high-speed slicing of loaves of bread fed approximately uniformly or evenly to reciprocating knives which are arranged to travel, as 10 it may be said, with the loaf when substantially not effective for slicing purposes, whereby the tissue or texture of the loaf and its several slices is efficiently retained and preserved.

Other objects of our invention are to generally 15 improve the construction of slicing machines, as will more particularly be pointed out as the description proceeds.

And with the above and other objects in view, our invention resides in the novel features of 20 form, construction, arrangement, and combination of parts hereinafter described and pointed out in the claims.

In the accompanying drawings (four sheets)—
25 Figure 1 is a plan view of a bread slicing machine embodying our invention;

Figure 2 is a side elevational view of the machine;

Figure 3 is an enlarged longitudinal sectional view of the machine taken approximately along 30 the line 3—3, Figure 1, the opposite ends of the machine being broken away;

Figure 4 is an enlarged fragmentary top plan view of the machine, showing the reciprocating knife-frames and associated parts, other parts 35 of the machine being broken away;

Figure 5 is a transverse sectional view of the machine taken approximately along the line 5—5, Figure 3, the lower portion of the frame being omitted;

40 Figure 6 is a horizontal sectional view of the machine taken approximately along the line 6—6, Figure 3, showing the driving mechanism;

Figure 7 is an enlarged transverse sectional view of the upper part of the machine taken approximately along the line 7—7, Figure 1;

Figure 8 is an enlarged fragmentary transverse sectional view of the upper part of the machine, taken approximately along the line 8—8, Figure 1;

50 Figure 9 is a fragmentary transverse sectional view of the machine taken approximately along the line 9—9, Figure 3;

Figure 10 is a diagram showing the position of the knife-actuating mechanism at the end of the 55 upstroke;

Figure 11 is a diagram similar to Figure 10, showing the position of the knife actuating mechanism at mid-stroke;

Figure 12 is a fragmental partly sectional view 60 illustrating a slightly modified arrangement of the hold-down device, the rear end of the gripping belt being broken away, and other portions of the machine omitted; and

Figure 13 is a fragmentary approximately 65 half-plan view of the modified hold-down device of Figure 12, taken approximately along the line 13—13, Figure 12.

Referring now more in detail and by reference 70 characters to the drawings, which illustrate a practical embodiment of our invention, the machine preferably includes two substantially rectangular-oblong side frames A rigidly tied together in suitably spaced parallel relation and whose front legs 1 and rear legs 2 are preferably movably supported from the floor on casters or 75 rollers 3 for facilitating placement of the machine.

The top rails 4 of the frames A support a table 5, which forwardly overhangs the front legs 1 and is supported therefrom by a pair of brackets 80 including horizontal marginal side angles 6 and inclined brace angles 7.

Fixed on a head-shaft 8 suitably journaled for rotation in and between the frame top-rails 4 at the rear end of the table 5, is a head-pulley 9, 85 and disposed in an aperture 10 in the front end of the table 5 and fixed on a shaft 11 journaled in suitable take-up bearings 12 adjustably mounted at the front end of the side-angles 6, is a tail-pulley 13, between and around which pulleys 9, 13, is stretched or reeved an endless carrier or feeding-conveyer-belt 14, whose upper run slidingly engages the upper face of the table 5. The loaves of bread B to be sliced are deposited along the front part of the belt 14 for transportation 90 thereby to the cutting mechanism, presently described, and by means of the bearings 12, the belt 14 may readily be suitably tensioned, a tensioning idler 15 being also suitably journaled in bearings 16 adjustably depending from an intermediate point of the table 5.

Presented forwardly from the frame-members A, is a pair of brackets 17 supporting a transverse guide-rod 18, and spaced rearwardly from the guide-rod 18, is a threaded shaft 19 journaled in and also between the brackets 17, a second transverse threaded shaft 20 spaced forwardly from the head-shaft 8 being also journaled in and between the frame-members A. 105

Each of the shafts 19, 20, has opposed series 110

of right and left-hand threads, at each of which each respective shaft 19, 20, has threaded engagement with an arm 21 presented from respective pairs of inverted substantially U-shaped saddles 22 disposed at the opposite end portions of longitudinal struts each forming with its conjoined end members one of a pair of longitudinally extending transversely spaced conveyor carriages 23 arranged on opposite sides of the belt 14. Each saddle 22 is slidably mounted on one of the respective shafts 8 and 18 in such manner that, on suitable rotary actuation of the threaded shafts 19, 20, the carriages 23 may be laterally shifted, that is, simultaneously advanced toward 15 or retracted from the belt 14.

Each carriage 23 is provided at its opposite ends with an endwise opening laterally inwardly inclined C-shaped yoke 24, whose lower leg is preferably a part of the subjoined saddle 22. Each 20 yoke 24 rotarily supports a pulley 25, and a gripping-belt 26 is stretched or reeved over the opposite end pulleys 25 of each carriage 23, the inwardly facing runs of each belt 26 overhanging the feeding-belt 14 at the rearward portion 25 of its run for yielding gripping engagement therebetween of the respective loaves of bread B carried by the feeding belt 14, as best seen in Figures 7 and 8.

The rear pulley 25 of each carriage 23 is preferably fixed on a shaft 28 journaled in the respective yoke 24 with its lower end projecting between the depending legs of the saddle 22 and carrying a bevel gear 29, which meshes with a bevel gear 30 splined to the shaft 8 and backing 35 against one of the depending legs of the saddle 22, as best seen in Figure 7. Actuation of the head shaft 8 for movement of the feeding belt 14 will accordingly actuate the pulley shafts 28 and thereby effect movement of the gripping 40 belts 26 in a direction and at a speed corresponding to and co-operating in unison with the movement of the loaf-supporting or feeding belt 14.

To prevent slippage of the belts 26 on the pulleys 25, each pulley 25 is preferably provided 45 with a circumferential series of radially presented pin-teeth 31, and each belt 26 is provided with a complementary series of pin-receiving apertures 32, thus providing for a positive driving-connection between the respective belts 26 and 50 their supporting pulleys 25, and also providing means for retaining the belts 26 in alignment on the pulleys 25. Preferably each belt 26 is constructed of rubber, leather, or the like, and is faced on its loaf engaging side with an unbroken 55 layer of canvas or like roughened material, as at 33, and spaced along the facing 33 approximately at distances corresponding to the width of a loaf are a series of transverse slots or bars 34, which serve to prevent slippage between the belts 26 60 and the loaves B gripped therebetween.

Contacting the back face of the loaf-engaging run of each belt 26 for substantially its length intermediate the pulleys 25, is a sag-preventing backing-bar 36 supported by suitable securing 65 means 37 from the longitudinal strut of the carriage 23.

Journaled in and between bearings 38 depending from each of the frame top-members 4, is a shaft 39 provided at its opposite ends with conveniently accessible hand-wheels 40, whereby the belts 26 may be selectively spaced or adjusted to accommodate the particular fed loaves B, the shaft 39 being also provided intermediate the bearings 38 with a sprocket wheel 41. Additional 75 sprocket-wheels 42 are mounted on the shafts 19,

20, and a chain 43 is operatively passed over the sprocket wheels 40 and 41 for simultaneous actuation of the shafts 19, 20, on rotation of the shaft 39, the chain 43 being preferably tensioned by an idler sprocket 44 adjustably supported on the adjacent frame top-member 4.

The head shaft 8 is driven by a suitable chain and sprocket arrangement 45 from a counter-shaft 46 journaled in suitable bearings 47 upstanding from a base-plate 48 supported on and between the lower horizontal members 49 of the frame of the machine, and consequently, on actuation of the shaft 8, the belt 14 and the belts 26 will be synchronously driven, as described.

The countershaft 46, in turn, is driven by a suitable chain and sprocket arrangement 50 from a cam-shaft 51 journaled in bearings 52 upstanding from the base 48. The cam shaft 51 is geared, as at 53, to a jack-shaft 54 journaled in bearings 55 supported on the base 48, the jack-shaft 54 being belted, as at 56, to a suitable prime mover, as an electric-motor 57, supported on a bracket 58 forwardly presented from the base-plate 48.

The cam shaft 51 is disposed transversely the machine and at one end carries a fly wheel 59; and mounted on the shaft 51 between the bearings 52, is a pair of cams 60, which preferably comprise oppositely disposed eccentric discs adapted to circumferentially engage respective rollers 61 intermediately carried by a pair of oscillatory levers 62, 63, each pivotally mounted at an end on respective bearings 64, 65, upstanding from the base 48. Both bearings 64, 65, are disposed forwardly of the shaft 51, the bearing 64, however, being more forwardly presented than is the bearing 65, as best seen in Figure 2. The lever 62, pivoted to the bearing 64, is correspondingly longer than the lever 63, which latter is pivoted to the bearing 65.

The levers 62, 63, are adapted for oscillation at their respective free ends in the plane of reciprocation of respective confronting transverse reciprocatory knife-frames 66, 67, one frame, as 67, being forwardly in the machine from the other frame 66, the forward frame 67 carrying a depending arm 68 pivotally connected, as at 69, to the free end of the shorter lever 63 and the rearward frame 66 carrying a like arm 68 having a pivotal connection 69 with the longer lever 62. Thus, with equal lift of the cams 60, the frames 66, 67, are alternately actuated in equal strokes.

Preferably the rollers 61 are rotarily mounted in yokes formed in the respective levers 62, 63, and to each yoke is also attached a clevis 70, which, in turn, is pivotally connected to an end of a floating lever 71, whose other end is pivoted to a link 72 pivotally depending from one end of a transverse frame member 73. Intermediate its ends, the frame-member 73 carries a swivel eye 74 rockably supporting a transverse semi-elliptic spring or tension member 75, whose opposite ends are pivotally shackled or link-connected, as at 76, each to an intermediate point of the respective levers 71, as best seen in Figure 9. The spring 75 is initially tensioned to resiliently engage the rollers 61 with the cams 60, and as the one lever 62 is lifted when the other lever 63 drops, the rockable spring 75 oscillates correspondingly without flexing, thus avoiding alternating stresses tending to cause fatigue of the metal and possible fracture thereof.

Transversely supported by and between the rear frame members 2, is a shelf-angle 77 suitably apertured, as at 78, for reciprocatory move-

ment therethrough of the arms 68, each arm 68 being guidingly engaged transversely to the oscillating plane of the respective levers 62, 63, by opposed flat-faced rollers 79 rotarily supported on opposite sides of the arms 68 by boxes 80 mounted on the shelf 77, as best seen in Figures 5 and 6. Lateral shifting of the arms 68 is thus prevented; however, the arms 68 may shift forward and back on the faces of the rollers 79 correspondingly to the arcuate displacement of the ends of the levers 62, 63.

From the opposite sides, and adjacent the upper margin, of each frame 66, 67, is presented a pin 81, on which are pivotally mounted the forward end of respective links 82, whose respective rear ends are pivotally mounted on respective pins 83 suitably supported by and between the bifurcated ends of brackets or standards 84 disposed rearwardly of the frames 66, 67, and upstanding from opposite sides of a delivery table 85, which preferably forms a continuation of the feed-table 5 and is supported on a pair of brackets 86 rearwardly presented from the respective frame-members A.

The levers 62, 63, and the links 82, are so mounted as to oscillate in like directions symmetrically about their fixed centers.

Each of the arms 68 forms a rigid unit with the respective frames 66, 67, which thus serve to connect the respective levers 62, 63, with their associated spaced links 82, whereby, on oscillation of the levers 62, 63, and links 82, the frames 66, 67, are as a whole vibrated or shifted alternately forward and back transversely to their reciprocating plane, such movement accruing by reason of the guiding action of the free ends of the levers 62, 63, and links 82 moving in their respective arcuate paths, whereby also the frames 66, 67, are caused to reciprocate in arcuate paths toward and from, or, as we may say, in a convex path relatively to, the forward or free-end of the machine and the loaves B to be sliced.

The opposing faces of the top and bottom members of the respective frames 66, 67, are provided with a series of complementary interfitting knife-supporting lugs 87, 88, each upper lug 87 being apertured for reception of an eye-bolt 89 secured to the upper end of, and for suitably tensioning, the respective blade or knife 90 whose lower end carries a transverse pin 91 adapted for engagement with the corresponding lower lug 88. The knives 90 carried by the respective frames 66, 67, are thus arranged in pairs disposed in transverse alternate alignment and interfittingly spaced in a common plane a distance equal to the slices to be cut, the several knives 90 having preferably a wave-like cutting edge presented forwardly for working engagement with the loaves B to be sliced fed by the conveyers 14 and 26.

The conveyers 14 and 26 move continuously in unison for feeding the loaves of bread B to and across the reciprocating plane of the slicing knives 90 at a uniform, even rate. As the knives 90 reciprocate, however, there is a period at the end of each stroke when the knives 90 are ineffective for slicing or cutting purposes.

During such period, however, the loaves B continue to advance on the knives 90, and the latter, unless withdrawn from the respective loaf at such time, will tear and bunch the soft tissues of the loaf, resulting in an imperfect product. To obviate such result is an object of our present knife actuating mechanism, by means of which the knives 90 are withdrawn from the loaf at the opposite ends of their stroke.

The travel of the knives 90 is diagrammed in

Figures 10 and 11 for the frame 67 and its actuating lever 63, the conveyer 14 being shown in the act of feeding the loaves B to the cutting plane of the knives. It will be seen that the frame 67 is at the top of its stroke and hence in its most rearward position a. As the frame 67 reverses its stroke, the conjoint action of the lever 63 and link 82 causes the frame 67 at mid-stroke to advance against the feed of the loaves B to the position b shown in Figure 11, while on completion of the down-stroke the frame is retracted with the feed of the loaves B substantially to the line a. On the up-stroke, the operation is repeated. Thus twice during each revolution of the actuating cam 60, the frame 67 moves its carried knives 90 into the advancing loaf B during the time when the endwise movement of the knives 90 is effective for slicing or cutting purposes, and during the time when the knives 90 have little or no endwise movement, they are rapidly retracted from the cut face of the loaf such a distance that, although the loaf is moving continuously toward the knives, the latter are substantially to the rear of and spaced away from the solid or uncut parts of the loaf a greater distance than the loaf will travel during the time interval required to reverse the stroke of the knives 90 and bring them again to cutting speed. Thus the knives have a simultaneous reciprocatory endwise movement across the feed, and a vibratory edgewise movement in the direction of feed, of the bread to be sliced. This applies also to the cutting action of the knives 90 carried by the oppositely reciprocating frame 66. The movement of each knife 90 provides an intermittent cutting action occurring substantially at the middle portion of its stroke, and an alternate intermittent disengagement from the uncut bread, occurring substantially at the ends of its stroke, such latter movement being at greater speed than the feed of the loaf, and the driving mechanism of the machine being arranged suitably for this purpose.

It will be seen that one frame 66 moves down while the other frame 67 moves up, each adjacent pair of the oppositely moving knives 90 cutting a slice of bread therebetween, from which it will be readily understood that the slices so cut are more or less free from the displacing effect of the slicing operation, one side of each slice being subject to a downward trend, while the other side of each slice is subject to an upward trend, neutralizing the first trend.

For supporting the loaves of bread B during the slicing operation, the delivery plate 85 is provided on its forward margin with loaf supporting means including a plurality of fingers 92 each being forwardly presented between the respective pairs of knives 90 and terminating at the head pulley 9 for reception therefrom of the loaves to be sliced. Disposed over the fingers 92 is a hold-down device 93 including a comb-like member 93 having a plurality of resilient fingers 94 each extending forwardly between the knives 90 and slightly up-curved at their forward ends for yieldingly engaging the upper side of each loaf as it is fed through the knives 90. Loaves of bread are not always uniform in the contour of their upper side, and in order that the comb 93 may yieldingly accommodate itself to the shape of the loaf as near as may be, the comb 93 is pivotally connected at each of its opposite ends to the respective depending legs of a pair of horizontal somewhat L-shaped arms 95 each pivotally mounted on a fixed transverse shaft 96 supported at its opposite ends on pin blocks 97 each slidable on an up-

standing support or rod 98 mounted on the respective brackets 84. A thumb-screw 99 threaded in each block 97 impingingly engages the respective rods 98 for adjustably securing the blocks 97 thereon.

5 Thumb-screws 100 are each threaded through a lug 101 rearwardly and laterally presented from the respective blocks 97 for impinging a rearward extension 102 of each arm 95 to adjust the 10 normal spacing of the comb 93 vertically from the feed-table 85. A pair of tensional springs 103 is mounted on the shaft 96, each having one end fixed to the shaft and the other end fixed to the respective arms 95 for yieldingly pressing or holding-down the comb 93 on a loaf of bread thereunder, in such manner that the comb 93 may rock transversely on the arms 95 to accommodate loaves having one side higher than the other and may yield or bias upwardly as a whole 15 to suit the different sizes of loaves being sliced. Preferably the comb-frame 93 at its rear edge is curved upwardly to facilitate the free exit of the sliced loaf thereunder. In such discharge movement, the sliced loaf of bread is laterally 20 retained in its pre-sliced shape and contour by a pair of upstanding retaining walls 104 adjustably mounted on the delivery table 85 and provided with forwardly extending resilient wings 104' for yieldingly engaging the opposite ends of the sliced loaf of bread emerging from the slicing knives. Preferably the walls 104 are of less height than the loaf of bread in order that the upper portion thereof may be exposed for suitable 25 manipulation in removing the loaf from the slicing machine.

On each side of the forward or loading portion of the feeding belt 11, is a pair of loaf guiding-walls 105, 106. The wall 105 is relatively short and is supported on a bracket 107 presented 30 forwardly from one of the carriages 23, preferably as a continuation of the upper member of the yoke 24. The other wall 106 extends forwardly substantially to the end of the belt 11 and is supported at its rear end by another bracket 35 107 supported from the other carriage 23. At its forward end, the wall 106 is supported on a foot-piece 108 adjustably mounted on the feed-table 5.

Thus, as the belts 26 are laterally shifted to accommodate the endwise dimensions of the 40 loaves to be sliced, the walls 105, 106, are correspondingly also shifted. The wall 105 is of reduced length relatively to the wall 106 in order that the loaves of bread may be slid from a tray laterally onto the belt 11 guidingly against the 45 long wall 106, the loaves being guided by the walls 105, 106, as they enter between the belts 26.

A debris receptacle 109 is removably supported on a pair of brackets 110 forwardly extending from the respective frame-members 1. The receptacle 109 is tensionally held at its opposite ends on the respective brackets 110 by a spring 111 having one end engaging the box and the other end engaging the adjacent bracket, the receptacle 109 being adapted to catch and receive 55 crumbs and like debris that may fall from the belt 14 and the belt 26, particularly the latter.

Another debris receptacle 112 is mounted transversely the rear of the machine and supported on the base plate 48 and also by the shelf angle 70 77, the receptacle 112 having a drawer 113 for removing the debris caught therein which may fall from the slicing knives 90.

75 Figures 12 and 13 illustrate a modified form of hold down device, characterized by yielding with the movement of the loaf, and including a comb-

like member 93' having a plurality of resilient fingers 94' each extending rearwardly between the knives 90. The comb 93' is upturned at its forward longitudinal edge 114 for yieldingly engaging the upper side of the loaves respectively advanced thereunder for slicing purposes, and the fingers 94' are slightly upturned at their rear ends for facilitating the discharge of the sliced loaf.

The comb 93' is preferably cut-out at its forward corners to accommodate the rear ends of the shiftable gripping belts 26, in order that the forward edge 114 may be disposed for engaging the loaves of bread before the same leave the gripping belts 26. The comb 93' at each end is 85 pivotally connected to the respective depending legs of a pair of horizontal arms 95', which are each bent around between and to clear the frame 67 and the rear ends of the respective belts 26, and thence forwardly, where each arm 95' is pivotally mounted on a fixed transverse shaft 96' supported over the belts 26 and at its opposite ends on pin-blocks 97' each slideable on a support or rod 98' upstanding from a side-member 4. A thumb-screw 99' threaded in each block 97' 100 impingingly engages the respective rods 98' for adjustably securing the blocks 97' thereon. Thumb-screws 100' are each threaded through a lug 101' forwardly and laterally presented from the respective blocks 97' for impinging a forward extension 102' of each arm 95' to adjust the normal spacing of the comb 93' vertically from the feed-table 85. A pair of springs 103' is mounted on the shaft 96' each having one end fixed to the shaft and the other end fixed to the 110 respective arms 95' for yieldingly pressing or holding-down the comb 93' on a loaf of bread thereunder in such manner that the comb 93' may rock transversely on the arms 95' to accommodate loaves having one side higher than the other and may yield upwardly as a whole to suit the different sizes of loaves being sliced. It will be seen that the arms 95' are pivoted forwardly of the point of engagement of the comb 93' with the loaf to be or being sliced, hence the comb 115 93' yields with the movement of the loaf with a minimum opposition thereto.

The use and operation of the several instrumentalities of the machine having been set forth as the description proceeded, we may particularly 125 point out that, due to the unique construction and efficient actuation of the cutting knives of the machine "pulling" of the bread structure is successfully avoided, and the capacity of the machine is greatly increased by reason of the 130 unimpeded movement of the loaves of bread through the cutting means.

A further particular to be noted is the unique hold-down device, whereby irregularly-shaped 135 loaves may be sliced with the greatest facility, and we might add that the other several features of the machine from time to time pointed out in the description have, in practice, proven to be of highly practical utility in the slicing of bread-loaves.

140 It will be understood that changes and modifications in the form, construction, arrangement, and combination of the several parts of the machine may be made and substituted for those herein shown and described without departing from the nature and principle of our invention.

Having thus described our invention, what we claim and desire to secure by Letters Patent is:

1. In a bread-loaf slicing machine, a standard, a reciprocatory knife-frame, a pair of oscillatory 150

- links pivotally connected to the standard and to the opposite sides of the upper end of the frame, an arm rigidly depending from the frame, means including an oscillatory lever pivotally connected 5 to the arm for reciprocating the frame, and means including a pair of opposed members supported on the standard and engaging said arm for guiding the frame in its reciprocations.
2. In a bread-loaf slicing machine, a reciprocatory series of cutting-blades, means for reciprocating the blades, said means including an oscillatory lever and a cam for oscillating the lever, and means for yieldingly pressing the lever in operative engagement with its actuating cam.
- 15 3. In a bread-loaf slicing machine, in combination, reciprocatory series of interfitting cutting-blades, means including a pair of cam-actuated oscillatory levers for oppositely actuating said series of blades, and means including a rockably supported tensional member having its opposite ends operatively connected with said levers and oscillatory therewith for resiliently retaining the levers in operative engagement with their actuating cams.
- 25 4. In a bread loaf slicing machine, in combination, reciprocatory series of slicing-blades, means including a pair of cam-actuated oscillatory levers for actuating said series of blades, a rockable tensional member, and means including a pair of floating levers each connected at an end to a respective oscillatory lever and at an intermediate point to one of the opposite ends of said tensional member for resiliently engaging said oscillatory levers with their actuating cams.
- 35 5. A bread-loaf slicing-machine including in combination, a support, a feed-table on the support, a pair of rigid confronting frames, series of cutting blades interfittingly mounted in the frames, links having pivot-connection with the support and with the respective frames for piv-
- otally suspending and guiding the frames for movement thereof on the support transversely of the feed-table, levers having pivot connection with the support and with the respective frames, rollers on the levers, and mechanism including opposed cams for engaging said rollers for oscillating the levers for oppositely reciprocating the frames and their carried knives arcwise transversely to the feed-table.
6. A bread-loaf slicing-machine including, in combination, a support, a feed-table on the support, a pair of rigid confronting frames, series of cutting blades interfittingly mounted in the frames, links having pivot-connection with the support and with the respective frames for pivotally suspending and guiding the frames for movement thereof on the support transversely of the feed-table, levers having pivot-connection with the support and with the respective frames, rollers on the levers, and mechanism including opposed cams for engaging said rollers for oscillating the levers for oppositely reciprocating the frames and their carried knives arcwise transversely of the feed-table, said levers having pivot-connection with the support for equal stroke of 100 the frames on equal lift of the cams and the axes of the knives being offset from the pivotal axes of the frames.
7. In a bread-loaf slicing machine, a standard, a knife-frame, a pair of oscillatory links pivotally connected to the standard and to the opposite side of the upper end-portion of the frame, an arm rigidly depending from the frame, means including an oscillatory lever pivotally connected to the arm for reciprocating the frame, and opposed rollers mounted for rotation on the standard and engaging said arm for guiding the frame in its reciprocations.
